WELDER

Edward G. Beiderman, Detroit, Mich., assignor to
General Motors Corporation, Detroit, Mich., a
corporation of Delaware

Application March 30, 1936, Serial No. 71,705

8 Claims. (Cl. 219—4)

This invention relates to welders. It has for its object an automatic device which prevents the electrodes from being withdrawn from the work until the current has been cut off. It is true that this result has been obtained in the past as, for instance, a starting of the operation of the machine sets a cam shaft in motion which goes the complete cycle of operations before it is stopped. But so far as I know it is new to provide a fluid operated device to hold the apparatus to one complete cycle operation notwithstanding a release of pressure on the trigger or other operation initiating device.

This "non-beat" welder is especially valuable in automatic repeat welding for the operator may very well release the trigger right in the middle of a weld and were it not for the "non-beat" device an incomplete weld would result and also arcing. By the use of the "non-beat" control, the welding goes on until the current is off and the electrodes released in the customary way.

In the drawing:

Fig. 1 is a large longitudinal section of the tool.

Fig. 2 is a diagrammatic view of a repeat welder embodying the "non-beat" device.

1 and 2 are the electrodes, 1 supported by the piston 3. Referring to Fig. 2, it will be seen that when the trigger 4 is depressed it opens the poppet valve 5 against the air stream. This air stream comes from the slide valve 6, which is in a position in Fig. 2 to connect with the air supply. Air passes through the air line 7 to the "non-beat" cylinder 8 and the electrode cylinder 9 and the contactor cylinder 10. The fluid pressure causes the "non-beat" piston 12 to press against the trigger 4 and hold the trigger and the valve open even when the operator's finger is released from the trigger. The contactor piston 13 rises in its cylinder and forces the primary switch 14 closed for a given length of time. This time depends on the inclination and length of the face of the cam 15, the air pressure and the size of the opening allowing the air to enter in the cylinder 10. When the cam 15 passes behind the roller 16, the spring 17 forces the switch open. Here the collar 17a picks up the nuts 18 on the end of the valve shaft 19. This moves the slide valve 20 to its uppermost position, in which position the passage 21 will register with the port 22. The air will then go into the electrode cylinder 9 in front of the piston 3 and the air will escape out of the contactor cylinder 10 and the "non-beat" cylinder 8 through the conduit 7 back to the port 23 which port of the

slide valve casing will now be open to the atmosphere.

As soon as the pressure is released behind the contactor piston 13, the spring 24 snaps the cam 15 by the switch arm which has a one-direction movement finger 25 which allows the cam to snap by the switch without moving the switch. Collar 17 now strikes the nuts 28 and forces the slide valve 20 back to the position shown in Fig. 2. The pressure now closes the poppet valve 5 and thrusts the trigger 4 back to its inoperative position.

It will be apparent that as long as the finger pressure is kept on the trigger 4 the valve 5 will remain open and consequently the cycle of operations will be automatically repeated, in fact, they can be repeated so rapidly as to achieve 400 or more welds a minute. The welds can be made in such quick succession as to be practically a stitch weld. By regulating the speed of the exhaust in the contact cylinder the speed of the repeats can be altered; the faster the air gets out of the contact cylinder the faster the machine will repeat; the faster the air gets in the contact cylinder the less the welding time and conversely the slower the entering of the air the longer the welding time. However I make no claim in this application to the contacting cylinder and timer or the regulation thereof, nor the repeat welding, nor the control of the repeats with the contactor piston and the slide valve. This last is the subject matter of a separate application No 58,916 filed January 13, 1936.

What I claim is:

1. In a welding machine the combination of a pair of fluid operative electrodes, a fluid operated electric timing means, means for supplying electrical energy to the electrodes when the timer is on, a trigger for controlling the fluid pressure, and a "non-beat" device in the form of an air cylinder and piston controlled by the electric timing means to keep the trigger in operative position until the timer throws off the current.

2. In a welding machine the combination of a pair of fluid operative electrodes, a fluid operated electric timer, means for supplying energy to the electrodes when the timer is on, a trigger for controlling the fluid pressure, a "non-beat" device in the form of a fluid-controlled member controlled by the timer and which keeps the the trigger in operative position until the timer throws off the current, and a fluid reversing valve automatically operated by the pressure for continuously repeating the welding operation

as long as the trigger is kept in operative position.

3. In a repeat welder, the combination of a pair of electrodes, means for bringing the electrodes together and separating them, means for furnishing current and timing it in consonance with the closing of the electrodes, control means for initiating these operations, fluid-operated means coordinated with the timer for causing the continuous repetition of the welding operations and fluid-operated means operable with the last mentioned repeat control and which assures a completion of the weld before operations are stopped notwithstanding the operator's release of the control device.

4. In a welding machine the combination of a pair of fluid operative electrodes, an electrical timing means, means for supplying electrical energy to the electrodes when the timer is on, a trigger for controlling the fluid pressure, and a "non-beat" device controlled by the electrical timer and in the form of a fluid operated device which keeps the trigger in operative position until the timer throws off the current.

5. In a welding machine, the combination of a pair of fluid operated electrodes, a fluid operated electric timer, means for supplying electric energy to the electrodes when the timer is in the "on" position, a trigger for controlling the fluid pressure leading both to the fluid operated electrodes and the fluid operated electric timer, a fluid operated reversing valve for automatically reversing the fluid flowing to the electrodes as long as the trigger is held in the "on" position, whereby the tool continuously repeats as long as the trigger is held in the "on" position, and a fluid operated "non-beat" device coordinated with the timer for holding the trigger in the "on" position while the electric timer is positioned to supply the current to the electrodes.

6. In a welding machine, the combination of a pair of fluid operated electrodes, an electric timer including a fluid operated actuating member, means for supplying electric energy to the electrodes when the timer is in the "on" position, a trigger for controlling the fluid pressure leading both to the fluid operated electrodes and

the fluid operated electric timer, a fluid operated reversing valve for automatically reversing the fluid flowing to the electrodes as long as the trigger is held in the "on" position, whereby the tool continuously repeats as long as the trigger is held in the "on" position, a fluid operated "non-beat" device for holding the trigger in the "on" position while the electric timer is positioned to supply the current to the electrodes, and both the reversing valve and the "non-beat" device being operated by and controlled by the fluid operated member of the timer.

7. In a repeat welding machine, the combination of a pair of electrodes, pneumatic means for reciprocating the electrodes and also involving a fluid reversing valve pneumatically controlled, an electric timer also repeatedly operated in properly timed relation with the electrodes, a fluid pressure supply and valve for keeping the machine operating and repeating in an "on" welding cycle and an "off" cycle as long as the valve is held open, and a non-beat device tending to keep the valve held open at all times during said "on" cycle and releasing each time on the "off" cycle to permit the closing of the said valve and discontinuance of operations after the operator releases the valve.

8. In a repeat welding machine, the combination of a pair of electrodes, pneumatic means for reciprocating the electrodes and also involving a fluid reversing valve pneumatically controlled, an electric timer also repeatedly operated in properly timed relation with the electrodes, a fluid pressure supply and valve for keeping the machine operating and repeating in an "on" welding cycle and an "off" cycle as long as the said valve is held open, and a non-beat device in the form of a piston and connected means operated by the said fluid pressure and tending to keep the valve held open at all times during the "on" cycle of the apparatus and releasing each time on the "off" cycle of the apparatus to permit the closing of the said valve and discontinuance of operations after the operator releases the valve.

EDWARD G. BEIDERMAN.
